HYDRAULIC HOISTING APPARATUS

Herbert O. Day, St. Paul, Minn., assignor to St. Paul Hydraulic Hoist Co., Minneapolis, Minn., a corporation of Michigan

Application July 6, 1936, Serial No. 89,021

5 Claims. (Cl. 298—22)

This invention relates to hydraulic hoisting apparatus, wherein it is desirable to provide a construction for a hoist such as is used in hoisting dump bodies of motor vehicles or the like to discharge the contents thereof out of the dumping body. It is desirable that the hydraulic hoisting apparatus be constructed in a unit which may be mounted as such to the chassis of the motor vehicle upon which the hydraulic hoisting apparatus is to operate. Further it is important that the apparatus be so constructed as to compensate for weaving and for the strain upon the respective parts so that the hydraulic hoist will operate under complete control and with reliability when operated by the vehicle driver with the ordinary knowledge of operating the vehicle and without any essential information excepting the operation of the control valve means and clutch means for operating the fluid pump of the hydraulic hoist.

Hydraulic hoists on motor vehicles are subjected to severe use and I have designed this unitary hydraulic hoisting apparatus with compactness, strength, and a balanced lever means to withstand the strain and wear and tear to which the same is subjected, so as to provide efficient operation, as well as the necessary strength and balance in the operating parts.

A feature resides in providing a hydraulic hoisting apparatus wherein there are no multiplicity of tubular passages for the hydraulic fluid which can by vibration and strain break down and cause unnecessary leaks of the hydraulic fluid.

Further, a feature resides in providing a frame adapted to support the hydraulic hoisting unit with a reservoir cross beam adapted to form the base and mounting for the hydraulic cylinder. The cylinder of the hoisting apparatus is mounted between the side members of the frame while the reservoir supporting beam is pivotally secured to said frame. This permits the whole cylinder assembly, including the strong substantial reservoir base, together with the pump and master control valve to swing or pivot together in the operation of the hoist in raising or lowering the hoisting body. The unit includes a pair of triangular shaped plate levers having a peculiar construction to provide a very strong and substantial operating beam for carrying the heavy load to which they are subjected in raising the dumping body. These triangular plate levers are pivotally mounted at one corner of their triangular formation. Between the triangular plate levers I provide a built-up cross-head which is adapted to be connected to the outer end of the piston rod.

This cross-head is pivotally connected to another corner of the triangular plate levers. To the other corner of the triangular plate levers I pivotally connect a pair of built-up links which are constructed to overlap and fold on either side of the triangular plate levers along one edge thereof, while the outer ends of these links are connected to a shaft to space them parallelly apart and to connect their outer ends with the frame upon which the dump body is mounted.

The unitary construction of this lever and piston connecting cross-head means provides a balanced lever structure parallelly operating and extending on either side of the piston so that the same can fold up into a compact state and can be operated to hoist a dumping body over the center of gravity into a high dumping position without the necessity of restraining springs or cables, yet providing a complete balancing of the strain on the respective parts and a bracing thereof against uneven operation yet compensating for weaving in the operation of the motor vehicle.

The triangular plate levers, the cross-head, and the links, are built up of sheet plate-like portions which are welded together to form an exceptionally strong member. The triangular plate levers have bearings formed in each corner thereof, while the cross-head operates centrally between the triangular plate levers and the links fold down onto the triangular plate levers into a compact state. With plate levers and folding connecting links of this character, together with the pivotal mounting of the piston, I provide a hydraulic hoisting apparatus foldable into a very compact unit, yet having a leverage means adapted to lift a dumping body into a greater angle with the center of gravity carried over the pivotal mounting of the dumping body, the dumping body being fully controlled and hydraulically cushioned by the apparatus without any restraining means being necessary other than the lever and link connections and the cushioning action of the piston in the cylinder of the hoist.

The drawings illustrate the hydraulic hoisting apparatus in a manner to show the relative co-operating position and construction of the same.

Figure 1 is a perspective of the unitary hoisting apparatus with the levers in extended position.

Figure 2 is an end view of the hoist when folded into compact state, looking toward the outer end of the piston rod and connecting cross-head.

Figure 3 is an enlarged detail of a portion of the hoisting apparatus, showing in dotted lines

the extended piston rod, cross-head, levers, and frame for supporting the dumping body.

Figure 4 is an edge view of the triangular plate lever.

5 Figure 5 is a detail section of one of the triangular plate levers on the line 5—5 of Figure 4.

Figure 6 is an edge view of one of the link levers. Figure 7 is a section on the line 7—7 of Figure 6.

10 Figure 8 is a plan view of the cross-head. Figure 9 is a front edge view of the cross-head.

Figure 10 is a side view of the cross-head.

The lever and piston connecting cross-head means provides a construction as illustrated, wherein the hydraulic hoisting unit A includes a

15 horizontally disposed cylinder B mounted between the parallel angular frame members 10 to rotate on the shafts 11 which project from the reservoir beam C, while the cylinder B is mounted on one side of the beam C. This provides a

20 simple mounting for the cylinder B between the frame members 10 so that the cylinder can pivot between these members freely and be folded therebetween, so to speak, with the lever and piston connecting cross-head means D.

25 The lever and piston connecting cross-head means D includes a pair of triangular shaped levers 12 which are mounted between the frame members 10, being carried upon the shaft 13 which is pivotally connected at 14 to the de-

30 pending members 15 forming a part of the frame members 10. The triangular lever plates 12 are connected to the cross-head member 16 by means of the shaft 17 which extends through the bearing 18 formed in the lever 12.

35 The pair of triangular levers 12 are adapted to be connected to a pair of links 19 to pivotally connect at 20 one end of the links 19 to the triangular levers 12. The pair of links 19 are connected on the other end to the shaft 21 so as to space the

40 links 19 parallelly disposed from the pivotal connection 20 to the connection with the shaft 21. The ends of the shaft 21 are mounted in bearings 22 which are carried by the frame members 23. The frame members 23 form the longitudinal

45 stringers or frame portions upon which the dump body (not illustrated) is secured or mounted. The frame members 23 are adapted to be supported by the rotatable bearing brackets 24 which are mounted upon the shaft 25 and supported at the rear of the frame members 10.

50 The cylinder B is adapted to be centrally disposed between the frame members 10 and being pivotally supported by the reservoir beam C on the shafts 11 the cylinder is free to swing be-

55 tween the frame members 10 while the triangular plate levers 12 are disposed in parallel relation to each other mounted upon the shaft 13 in a manner to rotate parallelly with each other and equally spaced on each side of the cylinder B.

60 Then with the cross-head connection 16 between the triangular plate members 12, it will be apparent that the plate members 12 may be operated by the piston rod 26 through the connection of the cross-head 16 to operate the triangular plate levers 12 in the desired manner.

65 The triangular plate members 12 are built up of the side plates 27 which are parallelly disposed between the spacer plate members 28 which members are welded together to form an integral structure.

70 The plate members 28 are marginally spaced from the peripheral edges of the plate members 27 as illustrated in Figure 5 to form a channel-like shape at the marginal edge of the levers 12 when the parts are integrally welded together. At each of the corners of the triangular

plate levers 12, bearings such as 18, 29 and 30, are built into the triangular plate lever to form an integral construction with the plates 27 and the spacing plates 28. This provides a plate lever having a very strong construction, together with substantial bearings at the corners so as to form a lever connection with the piston wherein the connecting members may be held in line under heavy strain and load and to provide a lever and link connecting means with the operating 10 hydraulic cylinder without any lost motion or back lash in the operation of the hydraulic hoisting apparatus.

The links 19 are built up by the side plates 31 which extend parallel to each other and which are welded to the bearing sleeve 32 on one end and are held spaced apart by the plate web so that the side plates 31 extend parallel and are integrally connected to the web plate 33 and the bearing sleeve 32. The web plate 33 extends 20 angularly from the bearing 32 toward one side of the side plates 31, terminating at 34 at the edge of the plates 31 and spaced from the ends 35 which project beyond the end 34 of the web plate 33 to provide an open space from the point 34 to 25 the extremity of the ends 35. The ends 35 are formed with openings 36 which are adapted to receive shaft-like bolts to pivotally connect the links 19 at 20 to one of the corner bearings of the triangular plate levers 12, as illustrated in 30 Figure 1. It will be apparent that the links 19 provide strong levers which are adapted to connect the triangular plate levers 12 through the shaft 21 to the frame 23 which supports the dumping body. Further, the links 19 are constructed so that they will fold over the outside 35 plates 27 of the triangular plate levers 12, as illustrated in Figure 3, which permits the folding of the levers and link means into a compact state on either side of the forward end of the cylinder 40 B and folding down between the sides of the frame 10. This construction permits my under-body hydraulic hoist to fold down into a compact state with the working levers equally spaced 45 on either side of the piston rod 26 and supported by strong bearings as well as providing lever and link means which have a substantial width to increase the bearing surfaces to hold the levers in line in operation.

I further provide a built up cross-head 16 which includes the centrally positioned shaft member 17 which extends in a manner to project on either side of the top and bottom plates 37. The plates 37 are welded to the shaft 17 and I provide web plates 38 which extend between the plates 37 and which are welded to the plates 37 as well as to the shaft 17. The central portion of the shaft is formed square at 39 so as to provide a suitable flat bearing for the plates 37 and have a welding connection with the webs 38. The webs 38 are positioned on either side of the shaft to strengthen and space the plates 37 apart. When these parts are all welded together they form a very strong cross-head 16 which is adapted to be connected to the piston rod 26 as illustrated 60 in Figure 3. The cross-head 16 provides the central spacer between the bearings 18 of the plates 12 to hold the triangular lever plates 12 apart and brace the same in line with the bearings 14 on the ends of the shaft 13.

70 The piston of the cylinder B is operated by hydraulic pressure from the pump E which is driven by the shaft 40 which connects with the power plant of a motor vehicle in a suitable manner, not illustrated. The fluid pressure from the 75

pump E is controlled by the master valve 41 which is provided with an operating lever 42 so as to set the valve in a manner to control the operation of the piston and connecting rod 26 to operate the triangular plate links 12 and the connecting link arms 19 to raise or lower a dumping body connected to the frame 23, the dumping body not being illustrated.

The unitary construction of my hoist with the triangular plate levers connected by the cross-head to the piston rod and to the member to be elevated into dumping position by the links 19, provides parallelly disposed lever and link means which extend in line, which are provided with wide bearing joints, and which fold together into a compact state or which are adapted to be extended to elevate the dumping body into a high angle without lost motion or back lash as the center of gravity of the dumping body is carried over the pivoting brackets which support the dumping body. The large triangular plate levers 12 brace the load as it is elevated against the tendency to twist or weave, while the cross-head braces these triangular plate levers centrally between the ends and causes an even pull to be exerted against the operating links 19. In the raising or lowering movement of the hoist A, the cylinder B pivots on the shafts 11 through the reservoir tank beam C which firmly holds the cylinder B in the frame 10, bracing the cylinder while its piston operates the connecting plate levers and link members through its connecting rod 26 and the cross-head 16. The power of the cylinder B is carried through the plate levers 35 and links equally balanced on each side of the cylinder B to uniformly distribute the load on the connecting cross-head 16 without cramping the connecting rod 26 and with free pivotal movement through the same to the cylinder B even though the plate levers 12 and the connecting links 19 elevate the dumping body into virtually a perpendicular position if it is desired.

It will therefore be apparent that it is essential that the plate levers 12, the connecting links 19, and the cross-head 16, operate to balance the load on either side of the piston and to operate in line through the bearings which connect the piston of the cylinder B with the load so that when the cylinder B is filled with hydraulic fluid, the piston may act without lost motion to cushion the load carried by the lever and link means which permits a high dumping angle of the load without undue strain upon the hydraulic hoisting unit A. The body which carries the load is also controlled so that it can be pulled down out of dumping position by the power of the hoisting mechanism A, being perfectly balanced in said hoisting mechanism and cushioned at all times by the hydraulic fluid in said hoisting unit.

60 I claim:

1. A hydraulic hoisting apparatus including a cylinder, piston and piston rod, a cross-head mounted on the outer end of said piston rod having shaft ends projecting from the side thereof,

triangular plate-like levers having bearings formed in each of the corners thereof, said cross-head being mounted in the bearings of one of the corners of said levers, a frame for pivotally supporting one end of said cylinder, means for pivotally supporting said triangular plate-like levers at one corner to said frame, links connected on one end to the remaining bearing in said triangular levers and having their outer ends pivotally connected to a member adapted to be elevated into dumping position, said links being mounted so as to straddle and fold onto said triangular levers substantially throughout their length in the folded and lower position of said hoist, and said triangular levers acting as a brace 15 against lateral movement in the operation of the piston of said hoist to maintain the hoisting force in line in the operation of said hoist.

2. A hydraulic hoisting unit comprising a frame, a cylinder pivotally secured to said frame, a piston 20 and piston rod on said cylinder, a cross-head on said piston rod, a pair of levers pivoted to said cross-head said levers being pivoted to said frame, a body to be hoisted pivotally secured to said frame, and links connecting said levers to said 25 body, each of said links including a pair of spaced side members secured to straddle one of said levers through the greater part of its length, and intermediate members connecting said side members and supporting them in definite spaced relationship.

3. A link and lever connection between a frame and a body pivoted thereto, including a lever pivoted to said frame and a link connecting said lever and said body, said link including spaced 35 side plates mounted to straddle said lever at one end at all times, and means connecting said side plates, said last named means being positioned to permit said side plates to straddle said lever throughout a greater portion of its length when 40 said link and lever are pivoted together.

4. A link and lever connection for a frame and body pivoted with relation to the frame including a lever pivoted to said frame and a link pivotally connecting said lever and said body, said 45 link including a pair of spaced plates and means connecting said plates comprising a connecting web secured diagonally between said side plates to reinforce said plates throughout their entire width.

5. In combination with a frame member and a body member pivotally secured thereto a connecting means including a lever pivoted at one of said members, a link connecting said lever to the other of said members said link and lever mounted to provide slight relative angularity 55 therebetween when said body is folded against said frame, said link including a pair of spaced plates straddling said lever and a connecting means supporting said plates in definite spaced 60 relation and angularly disposed for engaging an edge of said lever when said body is folded against said frame.

HERBERT O. DAY.
